Charles C. Tomkinson
By his Attorney
E. W. Marshall

UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

EXPANSION SHIELD WITH INTERLOCKING CAP.

Application filed February 23, 1921. Serial No. 447,293.

To all whom it may concern:

Be it known that I, CHARLES C. TOMKINSON, a citizen of the United States, and a resident of Plainfield, county of Union, and 5 State of New Jersey, have invented certain new and useful Improvements in Expansion Shields with Interlocking Caps (Case C), of which the following is a specification.

This invention relates to expansion bolts 10 such as are commonly anchored within bodies of solid material like concrete or masonry and is particularly concerned with the construction of an expansion bolt shield and with a cap piece designed for attachment 15 thereto.

The invention aims to provide a simple and improved form of interlocking means between the expansion shield and cap member whereby interlocking engagement may be 20 effected by moving the shield members in a plane parallel to the plane of the cap or in other words radially of the bore or opening in the same.

Other objects and features of novelty of 25 the invention will appear from the detailed description thereof taken in connection with the accompanying drawings which form part of the specification and will be particularly pointed out in the appended claims.

30 In the drawings, Fig. 1 is a view partly in elevation and partly in section showing one embodiment of the invention.

Fig. 2 is a vertical section showing the shield members and cap ready to be assembled.

Fig. 3 is a plan view of the cap shown in the above figures.

Fig. 4 is a view similar to Fig. 1 but showing a slightly different embodiment of the 40 invention.

Fig. 5 is a vertical section showing the shield members and cap of Fig. 4 ready to be assembled.

Fig. 6 is a plan view of the cap shown in 45 Figs. 4 and 5.

Like characters of reference designate like parts throughout the several views.

The expansion shield is shown as comprising two semi-cylindrical members 10. The 50 shield may have any desired exterior configuration and it may be expanded by any suitable means,—for convenience of illustration it has been shown as of plain cylindrical form. The cap preferably comprises 55 a plate-like member 11 of circular form, a

center opening or bore 12 being provided therein through which an expanding screw bolt or lag screw (not shown) may be passed as will be readily understood. Rising from the plate adjacent the opening therein is a 60 plurality of fingers 13 which are adapted to cooperate with the members of the shield for securing interlocking engagement. In the form of the invention shown in Figs. 1 to 3 the terminals of the fingers are bent 65 outwardly to form hooked members 14 and the shield members 10 are provided with perforations 15 to receive them. The shield members 10 are brought into interlocking engagement with the fingers 13 by being moved 70 toward the fingers, this movement being toward the axis of the cap bore or in other words, in a plane parallel to the plane of the cap. This manner of assembling the expansion shield and cap provides a connection 75 which positively holds the cap from disassociation with the shield when the latter has been inserted into the hole in the structure in which it is to be expanded.

In the modification shown in Figs. 4 to 6 80 the fingers 13' are provided with perforations 15' to receive radially projecting prongs 14' extending inwardly from the shield members 10. These prongs are preferably made by stamping out a portion of 85 the shield walls and bending the same inwardly from the end edges of the same. The method of assembly is the same as that of the other embodiment of the invention, namely the shield members are moved in 90 wardly toward the fingers until interlocking engagement is effected.

A cap of this kind covers the hole in which the expansion shield is used the end of which is apt to be ragged and unsightly, 95 and provides a neat finished appearance.

The form of interlocking connection above described is particularly desirable where the parts are made of sheet metal since the fingers 14 and prongs may be stamped out of 100 their respective members. The invention, however, is not necessarily limited to sheet metal shields and caps as will be readily understood. I, therefore, intend no limitations on the invention other than those imposed 105 by the appended claims.

What I claim is:

1. The combination with an expansion shield comprising a plurality of members, of a cap member having an opening there- 110

through, fingers projecting from the cap member adjacent the opening therein, and means between the fingers and shield members for effecting interlocking engagement therebetween when they are moved toward the fingers.

2. The combination with an expansion shield comprising a plurality of members, of a cap member having an opening there-
10 through, fingers projecting from the cap member adjacent the opening therein, and means between the fingers and shield members for effecting interlocking engagement therebetween when they are moved toward the fingers, said means including prongs ex-
15 tending from one of said members in direc-
tions perpendicular to the axes of the shield and cap member.

3. The combination with an expansion shield comprising a pair of semi-circular members, of a cap member having an opening therethrough, means for securing the cap member to one end of the shield comprising members extending radially and axi-
20 ally with respect to the axes of the shield and cap, said members being so arranged that interlocking engagement between the shield members and cap is effected by moving the shield members toward the axially
25 projecting members.

4. The combination with an expansion shield comprising a pair of semi-circular members, of a cap member having an opening therethrough, means for securing the cap member to one end of the shield comprising members extending radially and axi-
30 ally with respect to the axes of the shield and cap, said members being so arranged
35

that interlocking engagement between the shield members and cap is effected by mov-
40 ing the shield members toward the axially projecting members, said radially project-
ing members being spaced from the adjac-
ent end of the expansion shield.

5. The combination with an expansion shield comprising a pair of semi-circular members, of a cap member having an opening therethrough, means for securing the cap member to one end of the shield comprising members extending radially and axi-
45 ally with respect to the axes of the shield and cap, said members being so arranged that interlocking engagement between the shield members and cap is effected by mov-
50 ing the shield members toward the axially projecting members, said radially project-
ing members being spaced from the adjac-
ent end of the expansion shield, said axi-
55 ally projecting members extending from the
edge of the opening.

6. The combination with an expansion shield member comprising two separable ele-
ments, of a cap plate member abutting one
60 end of said shield, and means for securing the cap and shield in interlocked relation comprising a slot in one of said members at a point removed from said end of the shield and a prong on the other member adapted to enter said slot, said prong projecting radially with respect to the axis of the shield.

In witness whereof, I have hereunto set my hand this 18th day of February, 1921.

CHARLES C. TOMKINSON.

Witness:

I. B. Moore.
